UNITED STATES PATENT OFFICE.

JOHN A. DOTY, OF OAKVILLE, CANADA.

DESIGN FOR A FRUIT-BASKET.

SPECIFICATION forming part of Design No. 20,641, dated March 31, 1891.

Application filed January 29, 1891. Serial No. 379,580. Term of patent 14 years.

To all whom it may concern:

Be it known that I, JOHN ALBERT DOTY, a subject of the Queen of Great Britain, residing at Oakville, in the county of Halton and 5 Province of Ontario, Canada, have invented and produced a new and original Design for Fruit-Baskets, of which the following is a specification, reference being had to the accompanying drawing, forming part thereof.

10 The figure of the drawing represents a perspective view of my design.

The leading feature of my design consists in a fruit-basket provided with a series of rectangular splints, in which the alternating 15 longer splints extend beyond the rim of said basket.

In the drawing, 1 is the rim of the basket,

consisting of a double strip of material. Between these strips are secured the splints 2. Several of the splints 2 extend beyond the 20 upper edge of the rim 1, as indicated at 3.

The handle of the basket is indicated by numeral 4.

Having thus fully described my design, what I claim as new, and desire to secure by 25 Letters Patent, is—

The design for fruit-baskets herein shown and described.

Oakville, January 19, 1891.

JOHN A. DOTY.
